UNITED STATES PATENT OFFICE.

WILLIAM A. PARIS, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROLLER FOR ELECTRIC MOTORS.

1,037,181.

Specification of Letters Patent. Patented Aug. 27, 1912.

Application filed May 16, 1906. Serial No. 317,222.

To all whom it may concern:

Be it known that I, WILLIAM A. PARIS, a citizen of the United States, and a resident of Edgewood Park, in the county of Allegheny and State of Pennsylvania, have invented a new and useful Improvement in Controllers for Electric Motors, of which the following is a specification.

My invention relates to electric circuit controllers and has special reference to such devices as are adapted to effect suitable circuit connections for starting and operating electric motors.

One object of my invention is to provide a circuit controller, of the class above indicated, that shall be simple and durable in construction and adapted for relatively high voltage and large-current operation, and that shall act as an automatic circuit-interrupter under predetermined conditions.

Another object of my invention is to provide improved means for preventing the completion of the motor-running circuits previous to the completion and re-opening of the starting circuits, and means for operating the automatic tripping mechanism by a slight movement of the control handle toward the "off" position from the closed-circuit positions of the controller.

For the control of an induction motor of large size and relatively high voltage it is desirable to utilize a control device which combines the essential features of a high-voltage switching device and an automatic circuit-interrupter which may be dependent upon overload or other predetermined conditions for its actuation.

A form of controller which effects the aforesaid objective results may comprise two groups of movable contact members which may be similar to the contacts of well known oil-immersed circuit-breakers and one group of which, when brought into engagement with a corresponding group of stationary contact members, effects suitable motor-starting connections and the other of which, when in engagement with suitable stationary contact members, effects motor-running connections. The desired motion of the movable contact members may be

effected by a single operating handle-lever which occupies a central or "off" position when all the movable contact members are disengaged from the stationary members, a motion of the handle through a relatively short arc in either direction effecting the closure of the one or the other of the groups of contact members. With such a switching device, the motor supply circuits may be subjected to a serious overload if the motor-running circuits are closed before the motor has been accelerated by closing the starting circuits. In order to avoid possibility of thus overloading the line, I provide, according to my present invention, an arrangement of operating parts, such that the motor-running circuit connections may not be completed until the handle-lever has been first utilized in completing the motor-starting circuits, and in order to insure a quick interruption of the circuits when the motor is stopped, I further provide means for tripping the automatic circuit-interrupting device that is dependent upon a very short degree of movement of the operating handle from the closed circuit positions.

My invention is illustrated in the accompanying drawings in which—

Figure 1 is a front elevation, with the case broken away, of a circuit controller constructed in accordance therewith; Fig. 2 is a similar side elevation of the controller shown in Fig. 1 and Fig. 3 is a front elevation of the overload adjusting and operating handle mechanisms. Fig. 4 is a perspective view of the operating levers and release mechanism of the controller shown in the other figures.

Referring to the drawings, the controller illustrated comprises an insulating plate or slab 1 mounted in a substantially horizontal plane and attached to a casing section 2 which acts as a supporting frame for the operating parts and which may be attached to a rigid wall or frame structure. A group of stationary terminals 3, to which motor supply line leads may be attached, are fixed to the insulating plate 1 and are connected by flexible conductors 4 to two groups of movable contact members 5 and 6. The mov-

able contact members in each group are interconnected, in a well known manner, by insulating strips and are moved in vertical planes by connecting rods 7 and 8 which 5 pass through openings in the insulating plate 1 and the upper extremities of which are attached to two similar operating levers 9 and 10. Groups of coöperating stationary contact members 11 and 12 are adapted to 10 be respectively engaged by the groups 5 and 6 of movable contact members and are fixed to the insulating plate 1. The stationary and movable contact members may be of any suitable construction and are preferably 15 inclosed in a tank 13 which is attached to the casing section 2 and may be filled with oil or other suitable insulating fluid.

The operating levers 9 and 10 are pivotally mounted near one end upon a stationary 20 shaft 14 and their opposite extremities are attached to the upper ends of the connecting rods 7 and 8. The actuation of these levers is effected indirectly by a handle lever 15 which is rigidly attached to a shaft 16. 25 The operating lever 9 may be rotated about the shaft 14 by means of a toggle lever 20 which comprises a pair of links 17 having a slot and pin connection to an intermediate point 18 in the lever 9 and a lever arm 19 to which the opposite ends of the links are 30 pivotally connected. The arm 19 of the toggle lever 20 is pivotally mounted upon a shaft 21 and an arm 22 of this lever is connected by a main driving link 23 to a lever 35 24 which is fixed to the shaft 16 and is rotated therewith by the action of the operating handle 15. In this way, a relatively small movement of the operating handle 15 in one direction effects such a rotative movement of the shaft 16 that the toggle lever 20 raises the group 5 of stationary contact members into engagement with the corresponding stationary contact members. The 40 lost-motion connection between the lever 9 and the pair of links 17 permits a like movement of the handle lever in the opposite direction without in any way affecting the lever 9, provided the starting group of contact members is open. No means are 45 provided for locking the controller in the motor-starting position, so that the attendant must hold the handle at one end of its travel while the motor accelerates but a spring 50 latch 24^a is provided to engage a notch 25^a when the handle is at the opposite extremity 55 of its travel. This arrangement prevents a careless operator from leaving the controller when the starting circuits are closed.

One end of the toggle lever 20 is provided 60 with a projection 25 to engage either one of a pair of jaw projections 26 which are integral with a lever 27 that is rigidly fixed to the shaft 21 and one projecting arm 28 of which forms a bearing for an auxiliary

shaft 29. The other extremity of the shaft 65 29 is supported by a projecting arm 30 of a lever 31 which is also keyed to the shaft 21 near the opposite extremity from the toggle lever 20. A second toggle lever 32 is rotatably mounted between the levers 27 and 70 31 on the shaft 21 and is provided with a projecting arm 33 which is connected to an intermediate point in the operating lever 10 by a pair of links 34 and is also provided with a projecting arm 35, the end of which 75 is notched to be engaged by a trigger 36. A bell crank 37 is rotatably mounted upon the shaft 29 and is limited in its rotation by a projection 38 on the arm 30 of the lever 31 and is held against this projection 80 by a spring 39 which is coiled about the shaft 29. The trigger 36 is attached to the bell crank 37 and is so arranged as to engage the notched extremity of the arm 35 of the lever 32 when the shaft 21 is rotated 85 by the handle lever in passing from the "off" position to the starting position.

There is considerable lost-motion between the projection 25 on the toggle lever 20 and the jaws 26 of the lever 27 and the projection 25 normally engages one of the jaws 26 when the controller occupies the "off" position and causes the lever 27 and the shaft 21 to which it is fixed to rotate through a predetermined angle as the controller passes 90 from the "off" position to the starting position but is so arranged that the projection merely takes up the lost-motion between the jaws 26 and itself as the controller passes 100 from the "off" position to the running position. As the shaft 21 rotates in passing from the "off" position of the controller to the starting position, the shaft 29 and the bell crank 37 are rotated about the shaft 21 until the trigger 36 is brought into engagement 105 with the notched end of the arm 35 of the toggle lever 32. If the handle lever is now moved to the "off" position and from thence to the running position, the toggle formed by the arm 33 of the lever 32 and 110 the pair of links 34 is straightened so that the operating lever 10 is raised and the running group of movable contact members is brought into engagement with the corresponding stationary contact members.

A pair of similar overload release electromagnets 40 and 41 are connected in series with the motor-running circuits and comprise movable core members 42 and 43 to which hammer rods 44 and 45 are attached. 120 The distances of separation between the movable core members 42 and 43 and the stationary core members of the magnet are determined by a pair of similar forked adjusting levers 46 and 47 which engage nuts 125 48 on the upper ends of the hammer rods and which are keyed to a shaft 49. The rotation of the shaft 49 is effected by a

hand adjusting lever 50 which is on the outside of the case and is keyed to a shaft 51 that is connected to the shaft 49 by a link 52. When the controller occupies its running position one arm of the bell crank lever 37 is in line with the hammer rod 44 so that in case of overload the upper end of the hammer rod strikes the bell crank and the trigger 36 is withdrawn from the notched end projection of the arm 35 of the toggle lever 32. A lever 53, which is similar to the lever 37, is also attached to the shaft 29 and is located in alignment with the hammer rod 45.

15 A stationary projection 54 is attached to the casing section 2 and is adapted to trip the release mechanism whenever the controller is moved a short distance from its running position toward the "off" position, by 20 engaging a small tripping finger 55 which is pivotally mounted upon the bell crank lever 37 and is adapted to move the trigger 36 out of engagement with the arm 35 to allow the circuit to open without delay, in a manner 25 similar to that in which it is opened by the tripping magnets in case of overload upon the circuits. This arrangement is specially advantageous because the opening is independent of the action of the attendant in 30 throwing the controller from the running to the "off" position. Furthermore, the mechanism is always released in this manner so that it is impossible for the attendant to complete the motor-running circuits before 35 he has accelerated the motor by moving the controller to the starting position.

It will be observed that the length of the slots in the links 17 is such as to forcibly open the starting circuits, even if the 40 coöperating contact members should be welded together, before the running circuit can be closed. In normal operation the weight of the moving parts separates the contacts as soon as they are released.

45 Although, in the controller illustrated, the automatic release mechanism is only actuated in opening the motor running circuits, it may be of advantage to similarly arrange for making the opening of the starting circuits automatic as soon as the operating lever has moved through a small angle; and I desire that such variations and other variations which do not depart from the spirit of my invention shall be included within its 55 scope.

I claim as my invention:

1. The combination with a plurality of stationary contact members movable contact members coöperating therewith, an operating handle for effecting concurrent engagement of the coöperating members, and means for interlocking the handle and the movable contact members, of means for tripping said interlocking means the operation of which is

dependent upon a relatively slight movement of the operating handle toward its "off" position.

2. The combination with stationary contact terminals, a corresponding number of movable contact members coöperating therewith, an operating handle for effecting the engagement of the coöperating members, interlocking means between the handle and the movable members and a latch for the operating handle which normally holds the coöperating contact members in engagement with each other, of means for tripping said latch the operation of which is dependent upon a relatively slight movement of the operating handle toward its "off" position.

3. The combination with a corresponding number of stationary and movable contact members which are normally separated, an operating handle for effecting the engagement of the members and means for locking the members in engagement with each other, of means for permitting the members to separate independently of the operating handle the operation of which depends upon a relatively slight movement of the operating handle toward its "off" position.

4. In a controller for electric motors, the combination with an operating handle, stationary contact members, movable contact members and a device for locking said members in engagement with each other, of means for automatically releasing said device under predetermined conditions dependent upon either the current traversing the control circuits or upon a slight movement of the operating handle toward its "off" position.

5. In a controller for electric motors, the combination with stationary contact members, a corresponding number of coöperating movable contact members normally separated therefrom, a device for holding the members in engagement with each other and an operating handle lever, of means for tripping said device to release the movable members, the operation of which is dependent upon a slight movement of the handle.

6. In a controller, the combination with a corresponding number of stationary and movable contact members, an operating handle, and an automatic overload release mechanism, of means of actuating said mechanism to separate the contact members by the rotation of the handle through a small predetermined angle.

7. In a controller, the combination with a corresponding number of stationary and movable contact members, an operating handle, and an automatic overload release mechanism, of means for actuating said mechanism to separate the contact members and to open the control circuits by moving the operating handle through a small angle.

from the running position toward the "off" position.

8. In a controller for electric motors, the combination with a group of movable and 5 stationary motor-starting contact members, a group of movable and stationary motor- running contact members, and a single operating lever for effecting engagement between either group of movable contact members 10 and the coöperating group of stationary members, of means dependent upon a slight movement of the operating lever for automatically returning the motor-running group of movable contact members to open- 15 circuit position.

9. In a controller for electric circuits, the combination with two groups of separable contact terminals, and an operating handle lever, a predetermined movement of which 20 in either direction effects the engagement of one of the groups of contact terminals, of means for automatically separating one of said groups, the operation of said means being dependent either upon a predetermined value of current traversing the control circuits or upon a relatively slight movement of the operating handle lever.

10. In a controller for electric motors, the combination with two groups of stationary 30 and movable contact members, an operating handle lever, and means dependent upon the movement of the operating handle lever through a relatively short arc in the one or the other direction for severally effecting 35 engagement of the groups, of means dependent upon a slight movement of the operating handle from one of its extreme positions toward its central position for completely separating the coöperating contact members.

11. In a circuit controller, the combination with stationary terminal members, movable contact members adapted to co-operate with said terminal members and connected thereto by flexible conductors, 45 and an operating handle so connected to the movable contact members that movement thereof through a relatively small angle in one direction moves certain of the contact members into engagement with their coöperating stationary members, and a similar movement in the reverse direction moves the remainder of the movable members into engagement with their coöperating stationary members, of means for preventing the engagement of one set of said members until the other set has been moved into and out of engagement with each other. 50 55

12. In a controller for electric motors, the combination with a plurality of stationary 60 terminal members to which electrical energy is supplied, two groups of movable contact members connected thereto by flexible conductors, and two groups of coöperating sta- 65 tionary contact members from which energy

may be supplied for respectively starting 65 and operating an electric motor, of means for preventing the engagement of one group of coöperating contact members until the other group has been closed and opened.

13. A controller for electric motors comprising stationary contact members, movable contact members coöperating therewith and normally separated therefrom by the action of gravity when released, a manually-operated shaft and a lost-motion connection between the movable members and the shaft for positively separating said members if their normal separation is delayed. 70 75

14. In a controller for electric motors, the combination with stationary contact members and coöperating movable contact members normally separated therefrom when released; of means for releasing the movable contact members and for forcibly separating the contact members if their normal separation is delayed. 80 85

15. In a controller for electric motors, the combination with two stationary contact members and corresponding movable contact members normally separated therefrom, of means for actuating either of the movable members to engage the stationary members, said means serving also to forcibly separate one of the groups if its normal separation is delayed. 90 95

16. A starting controller for electric motors comprising a group of stationary and movable starting contact members, a similar group of running contact members, 100 an operating shaft, gearing between the operating shaft and each group of movable contact members, and means for automatically disassociating the operating shaft from the running contact members when the controller is moved from running position to "off" position. 105

17. A starting controller for electric motors comprising a group of stationary and movable starting contact members, a similar group of running contact members, 110 an operating shaft, gearing between the operating shaft and each group of movable contact members, and means for automatically disassociating the operating shaft 115 from the running group of movable contact members when the controller is moved from running to "off" position, and means dependent upon the movement of the controller to the starting position for reassociating the operating shaft and the running group of movable contact members. 120

18. In a controller for electric motors, the combination with coöperating stationary and movable contact members, manually-operated means for bringing the members into engagement with each other and means for holding the members in engagement. 125

ment, of a lost-motion connection between the manually-operated means and movable contact members for forcibly separating the contact members if their normal separation is delayed when the holding means is released.

In testimony whereof, I have hereunto

subscribed my name this 10th day of May, 1906:

WILLIAM A. PARIS.
